UNITED STATES PATENT OFFICE.

CARL Z. ALEXANDER AND EARL S. ALEXANDER, OF NEWARK, NEW JERSEY.

STEAM BOILER.

Application filed August 11, 1921. Serial No. 491,645.

To all whom it may concern:

Be it known that we, CARL Z. ALEXANDER and EARL S. ALEXANDER, citizens of the United States, and residents of Newark, county of Essex and State of New Jersey, have invented certain new and useful Improvements in Steam Boilers, of which the following is a specification, taken in connection with the accompanying drawing, which 10 forms part of the same.

This invention relates especially to boilers for steam heating, etc., of the type covered by the Alexander Patent No. 1,240,804 of September 25, 1917, in which one or more 15 geyser tubes are cast integral with or formed within the fire pot water jacket or boiler section more or less enclosing or surrounding the fire. In the case of cast iron or cast steel fire pots of water jacket construction, one 20 or more upwardly extending or substantially vertical geyser tubes may be formed or cast in the same, preferably adjacent the inner or heated surface of the fire pot which may be advantageously formed in some cases 25 with inward projecting corrugations or ribs to still further heat these geyser tubes. These geyser tubes are preferably of restricted area to give good water circulating or lifting action, and preferably communicate 30 at their lower ends with geyser chambers of greater area which may have similar heat receiving corrugations and projections and be located if desired in the hottest part of the fire pot. These geyser 35 chambers preferably communicate at their lower portions with the water jacket to receive water therefrom or from other parts of the boiler circulation, so that under normal operating conditions the development 40 of steam in the geyser tubes and chambers keeps a substantially constant automatic circulation of water and steam up through the geyser tubes to supply any desired form of supplemental heating or evaporating 45 means, which may be largely or wholly located above the normal water level of the boiler. A series of steam chambers or heating heads may be mounted above the fire pot for this purpose and provided with tortuous channeled or shallow water receiving 50 portions which may communicate with each other and with the water jacket, and any desired form of nipples or connections may conduct the water from the geyser tubes to one or more of these upper steam chambers

or heating units from which the unevaporated water may be returned to the water jacket if desired.

In the accompanying drawing showing in a somewhat diagrammatic way illustrative 60 embodiments of this invention,

Fig. 1 is a vertical section through a boiler taken along the line 1—1 of Fig. 3.

Fig. 2 is a partial horizontal section along the line 2—2 of Fig. 1.

Fig. 3 is a horizontal section along the line 3—3 of Fig. 1.

Fig. 4 is a similar horizontal section showing a modified construction.

Fig. 5 is a central vertical section showing 70 a modified construction; and

Fig. 6 is a horizontal section thereof on line 6—6 of Fig. 5.

The boiler may comprise any suitable fire pot water jacket or section such as 1 of cast 75 iron or other suitable material which may be mounted on the base or ash pit section 3 provided with the ash door 4. The fire pot water jacket may as indicated in Fig. 3 be formed with inwardly extending vertical 80 ribs or projections so as to have a corrugated inner surface, and this water jacket may be cast with any desired number of upwardly extending and preferably substantially vertical restricted area geyser tubes 85 39, which may advantageously be arranged adjacent the inner or heated surface of this water jacket while the external cooling thereof may be minimized if desired by making the water jacket thinner at these points, 90 so that the geyser tubes touch the outer surface which can be given a heavier coating or layer of asbestos or other heat insulating material. These geyser tubes should not be of so great area of cross section as 95 to prevent the efficient lifting action of the steam upon the water in the tubes, and although it is not in all cases necessary, these geyser tubes may at their lower ends communicate with enlarged area geyser chambers 100 45 open at their lower ends, so as to receive water from the water jacket and arranged to be heated by the adjacent hot part of the fire pot wall. The rest of the fire pot water jacket in this construction shown in 105 Fig. 3 comprises separated water chambers 48 which are connected at their top and bottom by yokes or rings such as the steam ring, 45 extending around outside of the geyser tubes as indicated in Fig. 1.

The supplemental heating units or steam chambers of any suitable construction, which may be used in connection with such a water jacket fire pot may be arranged above the same, so as to be heated by radiation or by the flue gases from the fire within the fire pot section. These supplemental heating units may comprise steam chambers such as 5 mounted vertically above the fire pot section in this case and connected therewith by a casing 41, having the flange 40 to be bolted or connected to the upper flange or top 16 of the fire pot section. These steam chambers may be formed with shallow water 10 receiving evaporating portions of any desired or suitable construction, and as shown in Fig. 2 a labyrinth arrangement of guide flanges and channels may be formed on the bottom of each of these steam chambers to 15 guide the water in zigzag paths over the heating surfaces, so that the water is heated and evaporated in thin sheets. The upper steam chamber 7 may as indicated be formed with ribs or projections 19, forming the channels 20 to guide the water as it flows inward and downward over the somewhat conical bottom 18 and finally passes through the nipple connection 25 to the lower head or steam chamber 17, where the water flows outward and downward in zigzag paths through the channels 35 formed by the projections or flanges 34 in which alternate end recesses or 20 passages 38 are formed as indicated in Fig. 2. This lower steam chamber may be 25 formed with the discharge recess 26 connected to the water jacket as by the pipe connections 28, 29 and 30 shown in Fig. 1. Flue passages are preferably arranged around and through these upper heating units, the lower steam chamber 17 having if desired such diameter that the gases may pass around it while any desired number of smoke flues 21 may be formed in the upper steam chamber 7 to carry the flue gases up into the smoke box 12, having the smoke pipe connection or neck 13 detachably or otherwise secured thereto. The steam pipe 47 may be connected to the upper steam chamber and the interior 44 of this chamber communicates 30 through the nipple 25 with the interior 33 of the one or more lower steam chambers employed.

Under operating conditions the fire heats the inner surface of the fire pot water jacket and generates steam in the geyser chambers 45 and communicating geyser tubes 39, so that this steam tends to lift the water in these geyser tubes and carry it up through the nipple connections 22 into one 35 or more of the upper heads or heating units to be further heated and evaporated therein. Also under forced firing, the evaporation in the other fire pot sections becomes sufficient to raise the normal water level 49, and 40 carry further quantities of water up through the nipples or connections 23 between the upper steam ring 48 and the steam chamber or heating unit 7 with which it is thereby connected. Thus still larger amounts of water are automatically fed to the supplemental heating units under forced firing of the boiler which further contributes to its efficient and desirable operation.

Fig. 4 shows another arrangement in which the fire pot water jacket is formed 45 with integral or cast-in geyser tubes 50, which may be entirely enclosed within the water jacket 51 so as to be in contact with water on their outer or rear surfaces away from the fire. This somewhat simplifies the 50 construction and gives freer communication between the water and steam sections of the main water jacket, although of course, somewhat less efficient heating of the geyser tubes is secured in this case. The relative 55 size of these geyser tubes 50 is somewhat exaggerated for the sake of clearness in this drawing, and for ordinary small or household boilers, these geyser tubes may have a cross sectional area of between one and two 60 square inches or so in most cases depending somewhat on their shape; it being of course, understood that where the thickness of these geyser tube passages is relatively small such as three fourths of an inch or less, their 65 width and cross section can be considerably increased in some cases.

Figs. 5 and 6 show another illustrative arrangement in which the geyser tubes are arranged adjacent the inner wall of the fire box water jacket and more or less protrude therefrom so as to be heated still more readily. The fire box section 52 of this water jacket construction may have the inner wall 53 more or less corrugated as by 70 forming therein projections or corrugations 55. The tubes may be more or less embedded in this inner wall of the water jacket if desired, and as illustrated these geyser tubes 64 which communicate at their lower 75 ends 62 with the water space 54 of the water jacket, project into the fire pot throughout at least part of their length and in some cases may be cast or formed so as to practically project into the fire box space as indicated, where still greater heat absorbing 80 capacity is desired. In some cases also the upper parts of these geyser tubes 65 may be bent inward so as to bridge the upper part 85 of the fire box and be joined by the junction box or chamber 68, all of these parts being located within the upper part of the fire box where the heat is apt to be greatest in starting the fire, so that the geyser tube action starts promptly and supplies even at first 90 considerable amounts of water to the steam chambers above. These steam chambers which may be of any suitable form and arrangement are illustrated as comprising two superimposed steam chambers 57, 67 joined 95

by a series of nipple connections 78, having the threaded bushings 79 to make tight connection if desired. The geyser tube or connection 69 which may have a push nipple connection with the flange 66 on the junction box, may have a similar connection with the flange in the bottom 72 of the upper steam chamber to which the water is supplied under firing conditions as indicated. 5 This water may be distributed throughout this steam chamber in thin sheets or streams by any suitable arrangement as by the ribs or projections 73, which form suitable channels 74 around which the water may run 10 before descending to the lower steam chamber 67 through the nipple connections 78. This lower steam chamber may have similar ribs or projections as 81 forming a series of water passages 80, the radial ribs 82 combined with the recesses 83 in the annular ribs forming a labyrinth or zigzag passage down which the water flows toward the center of the steam chamber as indicated by the arrows in Fig. 6. The discharge opening 85 receives this unevaporated water 15 which may thus pass through the passage 86 to the lower part of the water jacket through the pipe connections 28, 29 and 30. In this instance this lower steam chamber 67 is formed with a cast-in central collar 88 forming a passage 70 of considerable area through which the flue gases may pass so as to still further heat these parts of the steam chambers and the geyser devices located therein. Additional flue gases may pass 20 around the lower steam chamber 67 and then up through the smoke passages 93 in the upper chamber communicating with the smoke box 71 as indicated. Supplemental water 25 supplying connections may also be provided such as the nipples 76 connected to the water jacket and to the upper steam chamber 57, so that under forced firing conditions additional supplies of water are raised into the 30 interior 44 of this chamber so as to be fed therefrom to the lower chamber 67. If desired the threaded nuts or bushings 77 on these nipples may force the steam chambers together and they may be bolted to the fire box section as by the bolts 60 and nuts 61. The casing 87 may enclose the lower section 35 and steam supply pipes or connections 47, 89 may conduct the steam to the radiators, dryers, steam engines, or other devices where it is utilized.

This invention has been described in connection with a number of illustrative embodiments, forms, proportions, parts, arrangements, materials, construction and 40 methods of manufacture and use, to the details of which disclosure this invention is not of course to be limited, since what is claimed as new and what is desired to be secured by Letters Patent is set forth in the appended 45 claims:

1. A boiler comprising a substantially vertical corrugated cast metal fire pot water jacket having adjacent its inner surface a series of integral substantially vertical geyser tubes of restricted area extending to the outer wall of said water jacket, an enlarged geyser chamber communicating with the lower end of each of said geyser tubes and opening into said water jacket, a series of substantially horizontal steam chambers arranged above said fire pot water jacket, and having heating surfaces communicating with each other and with said water jacket, geyser tube connections connecting the upper ends of said geyser tubes with the upper steam chamber adjacent its periphery, a steam connection extending around said water jacket adjacent its upper end, connections between said steam connection and an upper steam chamber, and flue passages adjacent said steam chambers for the passage of gases from said fire pot. 70 75 80 85

2. A boiler comprising a cast metal corrugated fire pot water jacket having adjacent its inner surface a series of integral substantially vertical geyser tubes of restricted area extending to the outer wall of said water jacket, an enlarged geyser chamber communicating with the lower end of each of said geyser tubes and opening into said water jacket, a series of steam chambers arranged above said fire pot water jacket, and having heating surfaces communicating with each other and with said water jacket, geyser tube connections connecting the upper ends of said geyser tubes with the upper steam chamber adjacent its periphery, a steam connection extending around said water jacket adjacent its upper end, connections between said steam connection and an upper steam chamber, and flue passages adjacent said steam chambers for the passage of gases from said fire pot. 90 95 100

3. A boiler comprising a cast metal fire pot water jacket having adjacent its inner surface a series of substantially vertical geyser tubes of restricted area extending to the outer wall of said water jacket, a steam chamber arranged above said fire pot water jacket, and having heating surfaces communicating with said water jacket, geyser tube connections connecting the upper ends of said geyser tubes with the upper steam chamber, and flue passages adjacent said steam chambers for the passage of gases from said fire pot. 105 110 115

4. A boiler comprising a substantially cylindrical vertical fire pot water jacket having adjacent its inner surface a series of substantially vertical geyser tubes of restricted area, an enlarged geyser chamber communicating with the lower end of each of said geyser tubes and opening at its lower end into said water jacket, a series of substantially horizontal steam chambers arranged above said fire pot water jacket, and having inclined channeled heating surfaces communicating with each other and with the lower portion of said water jacket, gey- 120 125 130

ser tube connection nipples connecting the upper ends of said geyser tubes with the upper steam chamber adjacent its periphery, a steam ring extending around said water jacket adjacent its upper end, connection nipples between said steam ring and an upper steam chamber, and flue passages around and through said steam chambers for the passage of hot gases from said fire pot.

10 5. A boiler comprising a vertical fire pot water jacket having adjacent its inner surface a series of substantially vertical geyser tubes of restricted area, an enlarged geyser chamber communicating with the lower end 75 of each of said geyser tubes and opening at its lower end into said water jacket, a series 15 of steam chambers arranged above said fire pot water jacket, and having inclined heating surfaces communicating with each other 20 and with said water jacket, geyser tube connections connecting the upper ends of said 25 geyser tubes with the upper steam chamber adjacent its periphery, a steam ring extending around said water jacket adjacent its upper end, connection nipples between said 30 steam ring and an upper steam chamber, and flue passages around said steam chambers for the passage of hot gases from said fire pot.

6. A boiler comprising a vertical fire pot 35 water jacket having adjacent its inner surface a series of geyser tubes of restricted area, an enlarged geyser chamber communicating with the lower end of each of said 40 geyser tubes and opening into said water jacket, a series of steam chambers arranged 45 above said fire pot water jacket, and having inclined heating surfaces communicating with each other and with said water jacket, geyser tube connections connecting the upper 50 ends of said geyser tubes with the upper steam chamber adjacent its periphery, and flue passages around said steam chambers for the passage of hot gases from said fire pot.

45 7. A boiler comprising a substantially vertical cast metal fire pot water jacket having a series of integral geyser tubes of restricted area, an enlarged geyser chamber adjacent the heated surface of said water 60 jacket and communicating with the lower end of each of said geyser tubes and opening at its lower end into said water jacket, supplemental evaporating means arranged 65 above said fire pot water jacket, and having shallow water receiving heating surfaces 70 communicating with each other and with said water jacket, and geyser tube connections connecting said geyser tubes with said supplemental evaporating means adjacent its periphery.

60 8. A boiler comprising a cast metal fire pot water jacket having a series of integral geyser tubes of restricted area, an enlarged geyser chamber adjacent the heated surface 75 of said water jacket and communicating with the lower end of each of said geyser tubes and opening at its lower end into said water jacket, supplemental evaporating means arranged above said fire pot water jacket, and having shallow water receiving heating surfaces communicating with each other and with said water jacket, and geyser tube connections connecting said geyser tubes with said supplemental evaporating means adjacent its periphery.

65 9. A boiler comprising a fire pot water jacket having a series of geyser tubes of restricted area, an enlarged geyser chamber adjacent the heated surface of said water jacket and communicating with the lower end of each of said geyser tubes, supplemental evaporating means arranged above said fire pot water jacket, and having shallow water receiving heating surfaces communicating with each other and with said water jacket and geyser tube connections connecting said geyser tubes with said supplemental evaporating means.

70 10. A boiler comprising a substantially vertical water jacket fire pot section having adjacent its inner surface a substantially vertical integral geyser tube of restricted area, an enlarged geyser chamber communicating with the lower end of said geyser tube and communicating at its lower end 75 with said water jacket, a steam chamber arranged above said fire pot section and having heating surfaces communicating with said water jacket, and geyser tube connections connecting the upper end of said geyser tube with the steam chamber, and flue passages around said steam chamber for the passage of gases from said fire pot.

75 11. A boiler comprising a water jacket fire pot section having adjacent its inner surface an upwardly extending integral geyser tube of restricted area, an enlarged geyser chamber communicating with the lower end of said geyser tube and communicating at its lower end with said water jacket, a steam chamber arranged above said fire pot section, and having heating surfaces 80 communicating with said water jacket, and geyser tube connections connecting the upper end of said geyser tube with the steam chamber.

80 12. A boiler comprising a water jacket fire pot section having adjacent its inner surface an upwardly extending geyser tube of restricted area, a steam chamber arranged above said fire pot section, and having heating surfaces and geyser tube connections connecting the upper end of said geyser tube with the steam chamber.

85 13. A boiler comprising a fire box section having embedded therein a geyser tube communicating at its lower portion with a water space of said boiler, a steam chamber arranged above said fire box section and having heating surfaces above the normal water level in said boiler, said geyser tube communicating said steam chamber to auto-

matically supply water thereto under firing conditions.

14. A boiler comprising a fire section having adjacent the inner wall thereof a geyser device communicating at its lower portion with a water space of said boiler, a steam chamber arranged above said fire section,

and having heating surfaces above the normal water level in said boiler, said geyser device communicating said steam chamber, ¹⁰ to automatically supply water thereto under fire conditions.
